(57) **CLAIM**

The ornamental design of a collapsible container, as shown and described.

DESCRIPTION

FIG. 1 is a front side perspective view of the collapsible container of the present invention in a completely collapsed configuration;

FIG. 2 is a back side perspective view thereof in a completely collapsed configuration;

FIG. 3 is a front side perspective view thereof in a partially constructed configuration;

FIG. 4 is a front side perspective view thereof in a partially constructed configuration;

FIG. 5 is a front side perspective view thereof in a partially constructed configuration;

FIG. 6 is a front side perspective view thereof in a fully constructed configuration with an open top;

FIG. 7 is a front side perspective view thereof in a fully constructed configuration;

FIG. 8 is a back side perspective view thereof in a fully constructed configuration; and,

FIG. 9 is a close-up partial perspective view of a hinge.
